UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

COATING MACHINE.

Application filed October 25, 1924. Serial No. 745,903.

The present invention relates to coating machines, and especially to those in which an adhesive fluid is applied.

In such machines, when the work is to be coated upon but one side, it is customary to employ a rotatable roll to apply the cement or like fluid, and an opposite rotatable pressure-roll, which maintains contact of the work with the applying roll. Although these rolls run out of engagement with each other, drops of cement are likely to gather upon the pressure-roll and smear the surface of the work which should be kept clean. To avoid this, or to reduce its effect to a minimum, is an object of the invention. I therefore provide the pressure-roll with reduced peripheral projections, these presenting to the applying roll but a small cement-gathering surface, and with this associate a cleaning member conforming to the projections and held thereagainst by the frictional drag of the roll, which member promptly removes any of the coating substance which may adhere to the pressure-roll. For this cleaning member, some such yieldable material as felt is preferable, this readily adapting itself to the longitudinal contour of the roll.

In coating machines of the type to which this invention applies, the work travels from the applying member over a stationary support, with which the coated side contacts. This, especially when the pieces are thin, may interfere with their advance, so they will not be properly delivered to the conveyor or other apparatus which is to receive them. To render the delivery more positive is an object of the invention, this being attained by placing in co-operation with the fixed support a member, which extends through and is movable to advance the work over said support. As illustrated, this work-engaging member is rotatable, and when the supporting member is formed, as is usually the case, of spaced fingers, the member has projections extending between such fingers. I have found a brush having separated rows of fibers suitable for this purpose. The work-advancing member may also be made to serve as a stripper for one of the rolls acting upon the work for the application of the coating. In the present instance, this rotatable advancing member co-operates at its periphery with the applying member. It is sometimes desirable to

positively continue the advance of the work through the coating machine after it has left the fixed support, and to this end I may employ another advancing member, as a roll having peripheral projections, to reduce the area of contact with the coated side of the work, said member being situated at the opposite side of the support from the applying member.

In applying cement, there is likely to accumulate at the forward end of the support over which the work leaves the cementing machine, drops of the substance. From these may be drawn strings, which gather to such an extent upon the turning device or conveyor, by which the work is received, that its operation is affected. A further object of the invention is to furnish means for retaining these strings at the cementing machine. This I accomplish by associating with the support, at the opposite side from the applying member, a wall which extends into proximity with the line of travel of the work. Against this wall, the cement-strings are drawn and arrested. There may be associated with the wall an adjacent wall, spaced from and preferably lower than its companion. The two walls form opposite sides of a conduit, by which the retained strings are received, the cement being conveniently returned to the source of supply, as to a tank in which operates the applying member. When a roll is used as a portion of the supporting and work-advancing organization, the inner wall, which is also the lower, may contact with the roll and function as a scraper therefor. Both of the walls are shown as variable in position, so they may be caused to act most effectively.

One of the several embodiments which my invention may assume appears in the accompanying drawings,

Fig. 1 being a top plan view of a cementing machine to which this invention is applied;

Fig. 2, a broken end elevation of the forward extremity of the machine; and

Fig. 3, a vertical, longitudinal section on the line III—III of Fig. 1.

A tank 10 is so formed as to act both as a base for the machine and a source of supply of the cement or other substance to be applied to the work. Journaled transversely of this tank, about midway of its height, is a shaft 12, driven from any convenient

source of power and having fast upon it an applying member, furnished by a roll 14. The diameter of this roll is such that its lower portion lies in proximity to the bottom of the tank, while at its top it extends somewhat above the upper edges of the tank-walls. There are shown as extending longitudinally through it, openings 16, which aid in the agitation of the contents of the tank.

10 This tank is extended rearwardly from the applying roll, and has a cover 18, furnishing a table upon which the work-pieces are fed to the applying roll.

Rising from the sides of the tank, just at the rear of the roll 14, are standards 20, 20, which may be connected at their upper extremities by a cross-bar 22. Between the standards extends a spindle 24, about which a carrier 26 is mounted to oscillate. The 20 carrier has forwardly extending arms 28, 28, situated, respectively, near the opposite sides of the tank, and in which are journaled spindles at the end of a roll 30 acting as a pressure member to hold the work into contact with the roll 14 to receive the application of the coating substance. From the carrier 26 are two upward projections 32, 32, extending between opposite spaced walls 34 and 36 of a positioning member 38, which is 30 mounted to turn upon the spindle 24 at the end of the carrier. Between the bar 36 of the positioning member and the cross-bar 22, and seated in a depression in the latter, is a spring 40, which acts to turn the positioning member in an anti-clockwise direction, as viewed in Fig. 3 of the drawings, movement in this direction being adjustably arrested by a screw 48 threaded through the bar 34 and contacting with the cross-bar 22.

40 The carrier 26 is turned, to press the roll 30 downwardly, by springs 46, weaker than the spring 40, abutting at their ends against the projections 32 and against the bar 34, respectively, and held against displacement by screws 42. These springs urge the projections against stop-screws 44 threaded through the bar 36. The carrier may thus move with the positioning member against the spring 40, and may also move independently of the positioning member by compressing the springs 46. The organization is such that the normal relation of the roll 30 to the roll 14 may be determined by adjustment of the screw 48 and held by the spring 40. This adjustment adapts the apparatus to best operate upon groups of work-pieces in which there is a difference in thickness between the groups. Then, during the passage through the machine of these 60 groups of pieces, which may, in themselves, vary in thickness, the springs 46 are compressed by the movement of the roll 30, the spring 40 remaining unaffected on account of its greater strength. Since the condition of the springs 46 was not varied in the initial

adjustment, which involved only the spring 40, the pressure applied to the work, and, therefore, its effect in distributing the coating and determining the amount applied, remains substantially unaltered, whatever the 70 thickness of the particular piece of work. The roll 30 has a series of peripheral projections 50, the edges of which are reduced so that the total area over which they contact with the work is but slight. Consequently, if cement adheres to this roll, but little is transferred to the work. To clean the roll 30 if cement thus gets upon it, a strip 52, of some such yieldable material as felt, contacts with the down-going side. 80 This strip is shown as in the form of a wedge (Fig. 3), pressed into the space between the periphery of the roll and vertical walls of the members 26 and 36. Seated in this space, it conforms to the contour of the roll, 85 so that, as the latter rotates, the felt is dragged into the space by frictional contact with the roll 30 so that it is continually urged into tight engagement with the roll and the entire surface of the latter is 90 cleaned. The strip 52 is retained against upward displacement by some such elongated member as a rod 54, shown as forced between the strip and the projecting ends of the screws 44. The roll 30 is rotated 95 from the counter-shaft 56 by spur-gearing 58, the direction of movement of both this roll and the applying roll 14 being such that the work-pieces are fed forward from the table 18.

These rolls, which rotate at a considerable speed, eject the work, consisting, for example, of insoles used in making rubber-shoes, and upon a support, preferably furnished by a grid 62 in the form of a hollow frame, the work-engaging surfaces of which are furnished by the reduced upper edges of fingers 64 extending outwardly from one side of said frame in a direction opposite to the direction of travel of the work toward the applying roll. The fingers 64 lie above the down-going side of the applying roll, so that any cement dripping from them is returned to the tank. Other fingers 65 extend inwardly from the other side of the hollow frame in the same direction. When thin stock is operated upon, the momentum imparted to the pieces by the rolls 14 and 30 may not be sufficient to carry them out of the machine, especially in view of the adhesion of the cemented surfaces to the grid 62. To overcome this resistance, there is journaled in the sides of the grid a rotatable forwarding roll 66, the work-engaging surface of which is preferably furnished by brush-fibers arranged in spaced circumferential rows 68 between the grid-fingers 65 and projecting above their work-supporting edges inside the hollow frame of the grid 62. The roll 66 is rotated in the same direction 130

as the applying roll from the shaft 56 by way of a roll 70 journaled at the forward extremity of the tank. This roll 70 is rotated by sprocket-gearing 72 from the shaft 56, and, in turn, communicates its motion through a chain of spur-gearing 74 to the roll 66. These gears 74 may be protected by a cover 75 held in place by a screw 77. Upon the roll 70 are a series of longitudinally spaced, circumferential projections 76, the diameter of which is such that they extend to substantially the same height as the ends of the brush-fibers, though, as indicated in Fig. 3 of the drawings, they may be some-
 10 what below these, the downward incline facilitating the advance of the work. This roll 70, the direction of rotation of which is the same as that of the brush, effectively continues the travel of the work, carrying it
 15 from the machine to whatever apparatus is to receive it. At its lower side, the fibers of the roll 66 preferably come into close proximity to the surface of the applying roll 14. As a result of this, they act as a stripper, so, if by any chance a work-piece fails to be removed from the applying roll by the forward ends of the grid-bars, the brush-fibers, in their upward rotation, will engage this piece, and remove it from the applying
 20 roll, transferring it to the top of the grid. A scraper 78 may be associated with the brush, to remove the excess of cement from its fibers.

A certain amount of cement from the coated side of the work naturally adheres to the supporting elements, and at the last of these—the roll 70—strings of cement form, which, acted upon, probably by the air currents produced by the rapid travel of the work and by the advancing means, are drawn forward and gather upon the conveyor or other apparatus to which the work is delivered, tending to interfere with its action. To retain these strings at the cementing apparatus, the tank 10 is extended by a casing 80, shown as separable, this casing being of substantially the same width as the tank, and narrow longitudinally thereof. Its open top appears as somewhat above the adjacent end wall of the tank, while its lower portion communicates through an opening 82 with the bottom of the tank. Above the top of the casing, and at the forward side, is a string-arresting wall 84, the height of which is such that its upper edge lies in close proximity to the path of the work-pieces as they are thrown forward from the roll 70. Across the opposite or rear side of the casing is a second wall 86, shown as rearwardly inclined at its upper edge 88 and slotted (Figs. 1 and 2), so that it generally conforms to the longitudinal contour of the roll 70, acting as a scraper therefor. To both the walls 84 and 86 are connected
 25 end walls 90, extended downwardly into the casing and having vertical slots to receive transverse bolts 92. The outer ends of these bolts extend beyond the walls of the casing, and are threaded to receive wing nuts 94. By loosening these nuts, the walls 84 and 86
 30 may be varied simultaneously, both as to their height and inclination, and fixed in position by again tightening the nuts. In this way, their positions may be made such as to best intercept the cement-strings both
 35 from following the work in its advance, and from being carried back, when arrested, to the roll 70. The location of the edge 88 of the wall 86 also determines the manner in which it cleans the roll 70. Together, the walls 84 and 86 act as a conduit, continuing that formed by the casing 80 and returning the collected cement to the tank through the opening 82.

Insoles or other work-pieces laid upon the table 18 are advanced by the operator between the applying roll 14 and the pressure-roll 30. The screws 40 and 46 are respectively adjusted in accordance with the average thickness of the group of work-pieces to be operated upon and the pressure which it is desired to exert to distribute the cement over the work, so that, in all cases, the coating applied by the roll 14 will be substantially uniform. From the rolls 14 and 30, the work is advanced upon the fingers 64 and 65 of the grid, and positively moved forward by the brush-fibers 68, and then by the projections of the roll 76, which deliver it to the succeeding apparatus. The roll 30, because of the small area of contact of its projections with the work and the efficient manner in which it is cleaned by the yieldable strip 52, has little or no tendency to smear the uncoated side of the work, while a like limited contact of the brush and roll 70 with the opposite side of the work removes but little of its coating from the latter. Cement drawn from the machine in the direction of advance of the work is arrested by the wall 84, and passed between this and the wall 86 through the casing 80 to the tank, the inner wall not only serving to direct the retained substance through the casing, but also to scrape the roll 70. This retaining and roll-cleaning action is made more certain by the proper adjustment of the walls through their movement upon the bolts 92.

Having described my invention, what I claim as new and desire to secure by Letters Patent of the United States is:

1. In a coating machine, a rotatable applying roll, a rotatable pressure-roll co-operating therewith, a support for the pressure-roll provided with a wall disposed beside said pressure-roll adjacent to the work-engaging surface of said pressure-roll to form a constricted space, and a strip of yieldable material positioned between the

- wall of the support and the work-engaging surface of the down-going side of the roll so that the latter drags the material into said space to clean the roll.
5. 2. In a coating machine, a rotatable applying roll, a rotatable pressure-roll co-operating therewith, a support for the pressure-roll provided with a wall adjacent to the down-going side of the work-engaging surface of said pressure-roll to form a wedge-shaped space, a wedge-shaped strip of yieldable material forced into said space between the wall of the support and the work-engaging surface and retained in engagement therewith by frictional contact, and a retaining member contacting with the strip between the face of the support and the pressure-roll.
10. 3. In a coating machine, an applying member, a hollow frame provided with a set of supporting fingers projecting toward said member over which the work travels from the applying member, said fingers being spaced from one another and extending in the direction of travel, said frame having another set of fingers extending in the same direction within the frame, and a rotatable member having work-engaging projections extending between the fingers of one set.
15. 4. In a coating machine, an applying member, supporting fingers over which the work travels from the applying member, said fingers being spaced from one another and extending in the direction of travel, and a rotatable roll having separated rows of fibers extending between the fingers into engagement with the work.
20. 5. In a coating machine, an applying member, a co-operating pressure member, and a member rotatable in contact with the coated side of the work to advance it from the applying member, said rotatable member being arranged to engage work which is in contact with the applying member and strip it therefrom.
25. 6. In a coating machine, a rotatable applying roll, a tank for coating fluid in which the roll operates, and a rotatable member receiving coated work from the top of the roll to advance it, said member also co-operating with the down-going side of the roll to strip work from said roll.
30. 7. In a coating machine, a rotatable roll acting upon the work in the application of the coating, and a rotatable member arranged to advance work from the roll and to strip work from said roll.
35. 8. In a coating machine, an applying member, a stationary support over which the work travels from the applying member, and a member co-operating with and movable to advance the work over the support and also co-operating with the applying member to strip work therefrom.
40. 9. In a coating machine, an applying member, supporting fingers over which the work travels from the applying member, said fingers being spaced from one another transversely of the direction of travel, and a rotatable member having projections extending between the fingers upwardly into engagement with the work and downwardly into co-operation with the applying member to strip work therefrom.
45. 10. In a coating machine, an applying member, supporting fingers over which the work travels from the applying member, said fingers being spaced from one another and extending in the direction of travel, a work-advancing member movable between the fingers, and another work-advancing member acting after the first-named work-advancing member situated beyond the support from the applying member.
50. 11. In a coating machine, an applying member, supporting fingers over which the work travels from the applying member, said fingers being spaced from one another and extending in the direction of travel, a work-advancing member movable between the fingers, and a roll rotatable beyond the support from the applying member and having peripheral projections for contact with the work after the latter has been advanced by said work-advancing means.
55. 12. In a coating machine, a tank for coating fluid, an applying roll rotatable therein, a fixed support receiving coated pieces of work, a plurality of rolls journaled one beyond another in the direction of travel of the work from the applying member adjacent to said support, means for rotating the rolls to advance the work over said support to a point beyond the tank, and means for intercepting cement strings formed between the last roll and the work.
60. 13. In a coating machine, a tank for coating fluid, an applying roll rotatable therein, a plurality of rolls journaled one beyond another in the direction of travel of the work from the applying member, means for rotating the rolls to advance the work beyond the tank, a work-supporting grid between the fingers of which one of the advancing rolls projects, and means for intercepting cement strings formed between the last roll and the work.
65. 14. In a cementing machine, a cement-applying member, a support over which work is advanced from the applying member, and a wall situated at the opposite side of the support from the applying member and extending into proximity with but spaced below the line of travel of the work after it leaves the support.
70. 15. In a cementing machine, a cement-applying member, a support over which work is advanced from the applying member, a wall situated at the opposite side of the support from the applying member and extend-

ing into proximity with but spaced below the line of travel of the work after it leaves the support, and means arranged to permit the relation of the wall to the support to be varied.

16. In a cementing machine, a cement-applying member, a support over which work is advanced from the applying member, a wall situated at the opposite side of the support from the applying member and extending into proximity with but spaced below the line of travel of the work after it leaves the support, and a mounting for said wall permitting its height and angle to be varied.

17. In a cementing machine, a cement-applying member, a support over which work is advanced from the applying member, and adjustable walls spaced from each other at the opposite side of the support from the applying member, one of said walls extending upwardly into proximity with but spaced below the line of travel of the work after it leaves the support.

18. In a cementing machine, a cement-applying member, a support over which work is advanced from the applying member, and walls situated at the opposite side of the support from the applying member and spaced from each other in the direction of advance of the work, the outer wall being higher than its companion and extending into proximity with but spaced below the level of the upper side of the support.

19. In a cementing machine, a cement-applying member, a roll rotatable to advance work from the applying member, a wall situated at the opposite side of the roll from the applying member and contacting at its upper edge with said roll, and a second wall spaced from and extending above that first mentioned.

20. In a cementing machine, a cement-applying member, a roll rotatable to advance work from the applying member, a wall situated at the opposite side of the roll from the applying member and contacting at its upper edge with said roll, means arranged to permit the relation of the edge of the wall to be varied, and a second wall spaced from and extending above that first mentioned.

21. In a cementing machine, a cement-tank, a cement-applying member movable therein, movable means contacting with the cement-coated face of the work for advancing work from the applying member over the tank, and a conduit arranged to gather cement-strings formed at the advancing means.

22. In a cementing machine, a cement-tank, a cement-applying member movable therein, movable means contacting with the cement-coated face of the work for advancing work from the applying member over

the tank, and a conduit arranged to gather cement-strings formed at the advancing means, said conduit being arranged to return such gathered strings to the tank.

23. In a cementing machine, a cement-tank, a cement-applying member movable therein, movable means contacting with the cement-coated face of the work for advancing work from the applying member over the tank, and a casing carried upon and communicating with the tank beyond the advancing means, the upper end of the casing being arranged to receive strings formed at the advancing means.

24. In a cementing machine, a cement-tank, a cement-applying member movable therein, movable means contacting with the cement-coated face of the work for advancing work from the applying member over the tank, a casing carried upon and communicating with the tank beyond the advancing means, the upper end of the casing being arranged to receive strings formed at the advancing means, and means arranged to permit the string-receiving opening to be varied.

25. In a cementing machine, a cement-tank, a cement-applying member rotatable therein, a rotatable roll contacting with the cement-coated face of the work for advancing work from the applying member over the tank, and a casing carried upon and communicating with the tank beyond the roll, there being a wall at the forward side of the casing arranged to intercept cement-strings formed at the roll.

26. In a cementing machine, a cement-tank, a cement-applying member rotatable therein, a rotatable roll contacting with the cement-coated face of the work for advancing work from the applying member over the tank, a casing carried upon and communicating with the tank beyond the roll, there being a wall at the forward side of the casing arranged to intercept cement-strings formed at the roll, and an opposite wall contacting with said roll.

27. In a cementing machine, a cement-tank, a cement-applying member rotatable therein, a rotatable roll contacting with the cement-coated face of the work for advancing work from the applying member over the tank, a casing carried upon and communicating with the tank beyond the roll, there being a movable wall at the forward side of the casing arranged to intercept cement-strings formed at the roll and an opposite wall contacting with said roll, and a mounting arranged to permit the positions of the walls to be simultaneously adjusted.

In testimony whereof I have signed my name to this specification.

JOHN W. COSGROVE.
